UNITED STATES PATENT OFFICE.

TALBOT C. DEXTER, OF PEARL RIVER, NEW YORK.

AUTOMATIC PRINTING-PRESS CONTROLLER.

SPECIFICATION forming part of Letters Patent No. 699,913, dated May 13, 1902.

Application filed May 23, 1901. Serial No. 61,488. (No model.)

To all whom it may concern:

Be it known that I, TALBOT C. DEXTER, a citizen of the United States, and a resident of Pearl River, in the county of Rockland, in the State of New York, have invented new and useful Improvements in Automatic Printing-Press Controllers, of which the following, taken in connection with the accompanying drawings, is a full, clear, and exact description.

This invention relates to the class of devices applied to printing-presses for automatically arresting the action of said presses in case of defect in the feeding of the paper to the press; and the invention pertains more particularly to the automatic controller for printing-presses shown in my Letters Patent No. 665,072, dated January 1, 1901.

The object of my present invention is to simplify the construction of the mechanism of the automatic controller and at the same time obtain greater convenience and efficiency of operation; and to that end the invention consists in the improved construction and combination of parts hereinafter described, and summed up in the claims.

In the annexed drawings, Figures 1 and 2 are side elevations of a printing-press and feeding-machine equipped with my invention shown in its different operative positions. Fig. 3 is a plan view of the same. Fig. 4 is an enlarged side view of the stop mechanism. Fig. 5 is an enlarged section on line $x-x$ in Fig. 2. Figs. 6 and 7 are side views of a modification of the stop mechanism shown in different operative positions. Fig. 8 is a plan view of said modification. Fig. 9 is a vertical section on line $y-y$ in Fig. 8. Fig. 10 is an enlarged side view of the cast-off mechanism. Fig. 11 is a transverse section on line $z-z$ in Fig. 10, and Figs. 12 and 13 are detached side views of the two disks forming part of the cast-off mechanism.

Similar letters of reference indicate corresponding parts.

A represents the printing-press of the class termed "two-revolution" presses.

B represents an automatic paper-supplier or paper-feeding machine which may be of any suitable and well-known construction.

C denotes the feed-board, upon which the

paper is conducted from the feeding-machine to the printing-press.

D and D' represent the loose pulley and tight pulley, mounted on the driving-shaft, 55 from which motion is transmitted to the press mechanism by means of suitable gears in the usual manner and as indicated by dotted lines in Figs. 1 and 2 of the drawings.

F is the driving-belt, and F' is the lever by 60 means of which said belt can be shifted from one to the other of said pulleys for starting or stopping the press.

G represents the fly-wheel, which is fastened to the shaft of the aforesaid pulleys. 65

I and I' are shafts supported in suitable bearings $a-a$ and $a'-a'$ on the frame H and H' of the press and feeding-machine. By means of miter-gears on said shafts and suitable gears on the press and feeding-machine said 70 machine is caused to operate in unison with the press.

b designates the brake, which is designed to be applied to the fly-wheel G simultaneously with the shifting of the belt F from the tight 75 pulley onto the loose pulley D.

c represents the intermittent reciprocating press-tripping rod, which is connected to a transverse shaft c' , pivotally connected at its ends to the toggle-levers c^2 , which are arranged 80 at opposite sides of the press, to lift the impression-cylinder of the two-revolution press at regular intervals of time in the usual and well-known manner. (See Figs. 4 and 5 of the drawings.) Said rod receives motion from 85 a rock-arm d, engaging a notch d' in the under side of the rod. Said notch allows the rod to be lifted out of engagement with the rock-arm when desired to trip the impression-cylinder from its operative position. The lifting of the rod c is usually effected by a treadle e, secured to the upper end of a vertical stem e' and in a convenient position to be operated by the foot of the pressman standing on the usual footboard L on the side of the press-frame. The lower end of said stem is usually connected to the outer end of a lever fulcrumed on the press-frame and extending 95 with its inner end under the rod c. This lever, however, is dispensed with by my present invention, which effects automatically said lifting of the rod c, as well as the shift-

ing of the belt F to the loose pulley, said invention consisting, essentially, in the combination, with a printing-press and its actuating mechanism, of stop mechanism actuated 5 to automatically arrest the action of the press, a movable detent normally disposed to restrain said stop mechanism, a cast-off mechanism for throwing said detent from its normal position, a guard movable to and from a 10 position to restrain said cast-off mechanism, and a feeler actuated by the paper in transit to the press and controlling said guard.

The aforesaid stop mechanism consists of a pivoted tripper which is suitably connected 15 to the actuating mechanism to control the same and may be either of the form of disks T and T', pivoted at their centers to a stud s, projecting horizontally from the side of the press-frame, as shown in Figs. 4 and 5 of the 20 drawings, or of the form of an approximately horizontal lever T², pivoted intermediate its ends on the aforesaid stud, as represented in Figs. 6 and 7 of the drawings. When of the 25 form of a disk, as aforesaid, the connection with the actuating mechanism is made by means of a rod f, which is connected at one end eccentric to the disk and has its opposite end connected by a chain f³ to one of the arms of a bell-crank g, pivoted to a suitable 30 stationary support. The other arm of said bell-crank is connected to a horizontal extension F² of the foot of the belt-shifting lever F'. A chain or rod f' is connected at one end to the rod f and at the opposite end to a lever 35 f², pivoted at one end to a suitable stationary bracket and carrying on its free end the brake b. A spring-actuated push-rod h is suitably supported at one end on the press-frame and connected at the opposite end 40 to the disk T at a point approximately diametrically opposite the attachment of the rod f. Said rod h forces the disk to turn in a direction which causes the rod f to draw the belt F onto the loose pulley by means of the 45 bell-crank g and at the same time actuates the lever f² to apply the brake b to the fly-wheel G. When the aforesaid tripper is of the form of the lever T², as shown in Figs. 6 and 7 of the drawings, the shorter end of said lever is connected 50 by either a chain or a rod f' to one of the arms of a bell-crank h², whose other arm is connected to the rod f. A weight V, connected to the opposite end of the lever T², causes said lever to draw the rod f in the 55 requisite direction to shift the belt and apply the brake, as aforesaid. The movable detent, which is normally disposed to restrain said stop mechanism, I prefer to form of a latch i, which is pivoted at one end to the 60 side of the press-frame or to a plate P, attached to said frame. The free end of said latch is formed with a vertical offset or shoulder by which it engages a lug i' on the disk T or an arm i² on the lever T², according to the shape of the aforesaid tripper. The aforesaid engagement of the detent or latch i re-

strains the tripper T or T² from shifting the belt F onto the loose pulley.

For automatically tripping the impression-cylinder of a two-revolution press I mount 70 on the stud s a second revoluble disk T', as shown in Fig. 5 of the drawings, or a second lever T³, as represented in Fig. 8. Said disk or lever is actuated by a spring-actuated rod j or a weight j' and is restrained from acting 75 by a detent or latch j² in substantially the same manner as the disk T and lever T², hereinbefore described.

To automatically lift the press-tripping rod c by means of the disk T', I mount in suitable bearings on the press-frame a horizontal transverse shaft k, to which I attach an arm k', provided on its free end with a roller by which it bears on the under side of the rod c. To the outer end of the shaft k I fasten an 85 arm k², the free end of which is connected by a rod k³ to a stud k⁴, projecting from the side of the disk T'. When this disk is released from the detent j² and turned by force of the spring-actuated rod, the rod k³ is caused to 90 turn the shaft k by means of the arm k². Said movement of the shaft causes the other arm k' to lift the press-tripping rod c, and thus trip the impression-cylinder. When said tripping is to be effected by means of the 95 lever T³, as shown in Figs. 8 and 9 of the drawings, I connect said lever by a rod N to the free end of an arm N', fastened to a transverse shaft N², to the inner end of which is attached a second arm O, provided on its free 100 end with a roller which bears on the under side of the press-tripping rod c.

The cast-off mechanism for throwing the detents i and j² from their normal position or out of engagement with the tripper-disks T 105 T' or tripper-levers T² T³ consists of two disks l l', pivoted on a stud-pin l², projecting horizontally from a plate l³, fastened to the side of the upper part of the press-frame, preferably in proximity to the feed-board. To the side 110 of the disk l, at a point eccentric to the pivot thereof, is connected the upper end of a chain m or other suitable coupling, the lower end of which has extending from it two branches m' m', which are connected to the free ends of 115 the latches i and j². The periphery of the disk l is provided with a notch or shoulder n, suitably shaped to allow it to be engaged by a pawl n', pivoted to the end of a lever o, which is mounted at or near the center of its 120 length on the stud-pin l² and has its opposite end connected to the end of a rod o', whose opposite end is connected to one end of a lever p, which is pivoted intermediate its ends to a suitable bearing on the frame of the feeding-machine B and is provided on its opposite end with a roller, which rides on the face of a rotary cam p', supported on the aforesaid frame. Said cam receives motion from the actuating mechanism of the feeding-machine 125 by any suitable means. (Not necessary to be shown.) A spring-actuated rod p², connected 130

to the lever p , maintains said lever in contact with the cam p' , which imparts oscillatory motion to the lever p . The rod o' transmits said motion to the lever o , which by the engagement of its pawl n' turns the disk l part way on its pivot. The turning of this disk causes the detents or latches i, j to be lifted out of engagement with the tripper-disks or tripper-levers by means of the chain m . This release of said disks or levers allows them to automatically shift the belt to the loose pulley and also trip the impression-cylinder. To automatically control this stop mechanism, I employ a rock-shaft r , which extends across the feed-board adjacent to the impression-cylinder and is mounted at its ends in suitable brackets r' , secured to the feed-board or to a sheet-conveyer frame resting on the feed-board. To said rock-shaft are fastened forwardly-projecting arms r^2 , directly under the free ends of which are feelers t , pivoted on a transverse rod t' , which is supported at its ends on arms formed on the brackets r' . Said feelers normally rest with their lower ends on tongues w , which project from the end of the feed-board. The feelers are thus in position to be tilted by the paper in transit from the feeding-machine to the press. When the feelers are in said position, the arms r^2 of the rock-shaft r come in contact with the tops of the feelers, and thereby arrest the action of said rock-shaft. To the end of this shaft is attached an arm v , the free end of which is connected by a rod u to a stud-pin v' , projecting from the side of the disk l , pivotally supported on the stud-pin l^2 , as hereinbefore described. This disk receives oscillatory motion from a rotary cam R , disposed at the side of the cam p' on the feeding-machine and imparting oscillatory motion to a lever R' , from whence motion is transmitted to the disk l by a connecting-rod u' . The motion of said disk imparts rocking motion to the shaft r by means of the rod u . The periphery of the disk l has projecting from it a guard of the form of a cam l^3 , which during the oscillation of said disk is carried intermittently to a position to pass under a projection on the pawl n' , and thereby lift said pawl, so as to prevent it from engaging the notch or shoulder n on the disk l , which is thus left in a dormant position and free to allow the detents or latches i, j to drop into engagement with the tripper-disks T, T' or tripper-levers T^2, T^3 , and thereby prevent interruption of the action of the press. The aforesaid guard or cam l^3 is allowed to be carried into the position to prevent engagement of the pawl n' with the notch or shoulder n so long as the paper passes to the press and tilts the feelers t , so as to allow free movement of the rock-shaft r and guard-disk l ; but whenever either of the feelers fails to be actuated by a sheet and is thus allowed to remain in normal position the motion of the rock-shaft is arrested by the arm r^2 coming in contact with the upper end of the dormant feeler. The rock-shaft is thereby retained in a position which causes the connecting-rod u to lock the guard-disk l and prevent it from lifting the pawl n' out of engagement with the notch or shoulder n on the disk l , which is thus allowed to be turned by the lever o and in this movement lift the detents or latches i, j out of engagement with the tripper-disks or levers, which then automatically shift the belt onto the loose pulley and trip the impression-cylinder. Hence the actuating mechanisms of the press are controlled automatically by the feelers actuated by the paper in transit to the press. The two cams R and p' should be set in such position in relation to each other as to cause the guard-disk l to turn forward slightly in advance of the forward movement of the pawl n' , and thus insure the lift of said pawl before its arrival at the shoulder n of the disk l .

To allow the operator to again set the press in motion after it has been automatically arrested, as herein described, I employ the chain f^3 or other suitable flexible connection between the tripper and belt-shifting lever to allow the brake to be removed from the fly-wheel without exerting any stress on the belt-shifting lever, which can then be operated by hand to throw the belt onto the driving-pulley without any restraint from the brake. The brake is thrown from the fly-wheel by the operator depressing the treadle e , the stem e' of which is connected to the arms e^2 , fastened to the sides of the tripper-disks T, T' , as more clearly shown in Figs. 4 and 5 of the drawings. Said depressing of the treadle turns the tripper-disks back to a position to allow the latches i, j to reengage said disks and simultaneously pushes the brake from the fly-wheel. When the aforesaid trippers consist of levers T^2, T^3 , I pivotally connect said treadle to the ends of the shorter arms of the said levers, as shown in Figs. 6, 7, 8, and 9 of the drawings. A pressure applied to the treadle e by the foot of the pressman restores the tripper-levers to a position to allow the latches i, j to reengage said disks or levers, as aforesaid.

What I claim as my invention is—

1. In combination with a printing-press and feeder, the automatic stop mechanism, a tripper controlling said stop mechanism, and a detent movable to and from a position to restrain the action of the tripper, two disks disposed side by side and oscillating independently of each other, means for transmitting motion from one of said disks to the aforesaid detent, a guard carried on the other of said disks to and from a position to prevent transmission of motion to the detent, and a feeler actuated by the paper in transit to the press and controlling the motion of the guard-carrying disk.
2. The combination with a printing-press and its actuating mechanism, of a pivoted tripper-disk, a rod connected at one end eccentric to said disk and at the opposite end to the aforesaid actuating mechanism to control the same, means actuating said disk to

automatically arrest the actuating mechanism, a lug on said disk, a latch engaging said lug and restraining thereby the action of the disk, an oscillatory disk, means for transmitting motion from said disk to the latch to throw it out of engagement, a guard movable to and from a position to prevent said transmission of motion to the latch, and a feeler actuated by the paper in transit to the press and controlling said guard as set forth.

3. The combination with a printing-press and its actuating mechanism, of a pivoted tripper suitably connected to said mechanism to control the same, means actuating said tripper to automatically arrest the actuating mechanism, a movable detent normally disposed to restrain the action of said tripper, a pivoted disk provided with a shoulder on its periphery, an oscillatory lever provided with a pawl to engage said shoulder, means for throwing the detent out of restraining position by the movement of said disk, an oscillatory disk at the side of the shouldered disk and provided with a guard for throwing the pawl out of engagement, and a feeler actuated by the paper in transit to the press and controlling the said guard-disk as set forth.

4. The combination with a printing-press, an automatic paper-supplier, a feed-board and mechanism actuating said press and supplier in common, of a pivoted tripper suitably connected to said mechanism to control the same, means actuating said tripper to arrest said mechanism, a movable detent normally disposed to restrain the action of said tripper, a pivoted disk provided with a shoulder on its periphery, an oscillatory lever provided with a pawl to engage said shoulder, means for throwing the detent out of restraining position by the movement of said disk, an oscillatory disk at the side of the shouldered disk and provided with a guard for throwing the pawl out of engagement, mechanism imparting motion to said guard-disk, a rock-shaft disposed transversely over the delivery end of the feed-board, an arm attached to said rock-shaft, a rod connecting said arm to the aforesaid guard-disk, and a feeler actuated by the paper in transit to the press and controlling said rock-shaft as set forth.

TALBOT C. DEXTER. [L. S.]
